UNITED STATES PATENT OFFICE.

SVEN JULIUS STRID, OF CHICAGO, ILLINOIS, ASSIGNOR TO FRED MATHEWS, OF CHICAGO, ILLINOIS.

DROP SHAFT FOR HAND BRAKES.

Application filed May 2, 1925. Serial No. 27,587.

My present invention relates to hand-brake mechanism for railway cars and more particularly to such mechanism known as the drop-shaft type wherein the shaft carrying the hand wheel upon its upper end is adapted to be lowered from its normal position so that the wheel will be flush with or below the plane of the floor of the car body.

10 My invention is designed to provide a dependable support for the brake shaft when the latter is in an elevated position as in normal use, and this support may be readily manipulated to permit the lowering of the 15 shaft and hand wheel to the desired position whenever it is necessary to depress or drop the same. When the shaft is in a depressed or lowered position the support will lean or rest against the side of the shaft 20 so that whenever the shaft is raised to its normal or intended position, or slightly above such position the support will automatically drop by gravitation across the lower end of the shaft, thus rendering the 25 device proof against careless operation.

In connection with my specially designed adjustable support for the brake shaft, I have provided a novel disposition and mounting for the usual ratchet wheel and 30 pawl, and I have also provided a uniquely designed stirrup or step upon which the shaft support is carried and which stirrup or step is utilized for the mounting of a 35 brake gearing such as disclosed in United States Letters Patent No. 1,508,564 issued September 16, 1924, for a "gearing."

I prefer to carry out my invention in substantially the following manner, reference being made to the accompanying drawings that form a part of this specification.

In the drawings:-

Figure 1 is a vertical side elevation of my invention showing the same applied to the end of a flat car.

45 Figure 2 is a vertical end elevation of the structure illustrated in Figure 1.

Figure 3 is a vertical longitudinal section taken on line 3—3 of Figure 2.

50 Figure 4 is a horizontal or transverse section taken on line 4—4 of Figure 3 and looking downwardly in the direction of the arrows.

The end-sill of the car underframe is designated by the numeral 10, the floor as 11, 55 and the segmental shaped depression or re-

cess in the floor for the accommodation of the hand wheel, as 12. The hand-wheel 13, is of the usual type, as is also the brake-shaft or mast 14, the latter being preferably of rectangular shape with its longitudinal corners chamfered as illustrated in Fig. 4. The end-sill 10 is a channel beam with the web vertically disposed and just below the upper flange the web is provided with a horizontally elongated slot 15 in which the ratchet element 16 is disposed, and a cast-metal bearing bracket 17 is secured to the outer face of the sill just below the slot 15 to assist in supporting the ratchet element and through which the shaft or mast is rotatable and may also be moved longitudinally whenever raised or lowered. The pawl or dog 9 for cooperating with the ratchet 16 is pivotably mounted upon the bracket 17 as shown in Fig. 2. The ratchet element 16 is provided with an aperture through its center that is a counter-part of the cross-sectional contour of the shaft or mast so that the ratchet element may be rotated with the shaft or mast but will permit the latter to be moved transversely through it.

A triangular shaped brace 18, the edges of which are longitudinally flanged as indicated by dotted lines Fig. 1 is secured to the rear face of end sill 10 by means of one of the bracket flanges and said bracket extends away from the sill at substantially a right-angle thereto. The stirrup is a hollow cast structure formed preferably in two sections that are bolted or riveted together and connected to the end sill 10 and the brace 18. The basal flange of the bracket 18 has secured to it the horizontal and laterally extended member 19 of the upper half-member or section of the brake shaft 90 stirrup. This upper stirrup section is of substantially inverted U-shape when viewed from the end of the car as seen in Fig. 2, the horizontal web 20 thereof being disposed under the lower flange of sill 10 and 95 extends outwardly therefrom a short distance as seen in Fig. 1. Depending parallel flanges 21 extend downwardly from the ends of plate 20 and bracing lugs 22 extend upwardly from plate 20 in front of the sill 10 and are bolted or riveted thereto. The rear portion of the flat member or extension 19 is disposed below the horizontal basal flange of the triangular bracket 18 and is bolted or riveted thereto. The lower 100 105 110 115

2
section of the stirrup comprises a horizontal member 23 disposed parallel with the plate 20 of the upper section and at its ends is provided with upstanding flanges 24 that 5 overlap and are secured to the parallel plates 21 of the upper section, thus forming a structure of rectangular shape as seen in Fig. 2 of the drawings. An aperture 25 is formed in the plate 23 of the lower section of a diameter slightly greater than the diagonal dimension of the brake shaft or mast 14 which is rotatably mounted therein and is guided at its lower end thereby. A similarly bored bearing 26 is provided in 10 the plate of the upper section of the stirrup.

Depending from the under surface of plate 23 is a box-like structure 27 of rectangular shape in cross section and which is open at its bottom. The lower end of the 20 front wall of the box-like structure 27 is provided with horizontal inwardly extending flanges 28 that are spaced apart horizontally so as to provide a recess 29 that permits the shaft or mast 14 to be rotated 25 without interference when the latter is in a lower or dropped position. These flanges 28 provide stops or shelves for supporting the outer or free edge of a gate 30 that drops by gravitation when the lower end of 30 the shaft or mast has been raised above the edge of the opened gate. The gate is of rectangular outline as seen in Fig. 4 and upon its portion opposite the flanges 28 it is provided with hinge knuckles 31 through 35 which the hinge pin 32 passes and is engaged in the opposite side walls 33 of the box-like structure. A finger or handle 34 projects laterally from the edge of the gate between the knuckles 31.

40 When the shaft or mast 14 is in a raised position the gate 30 will be disposed horizontally and rest upon the flanges 28 so that the lower end of the shaft is supported by the gate. When it is desired to drop the 45 shaft the latter is raised slightly to permit the raising or opening of the gate and the shaft is then lowered to the desired position.

In this position, Fig. 3, the gate rests or inclines against the side of the shaft through 50 the action of gravity so that whenever the shaft is raised a distance sufficient to permit its lower end to clear the then upper edge of the gate the latter will fall to its normal position and rest upon the flanges 55 28.

55 In order to prevent the accidental withdrawal of the shaft from the guides and stirrup a stop pin 35 is inserted transversely through its lower end so that it projects upon opposite sides of said shaft and will 60 strike against the plate 23 of the lower stirrup section when the shaft is elevated too far.

An arm 36 of inverted U-shape in cross section extends rearwardly from the box-like 65 structure 27 and adjacent its extremity is

bored transversely to provide a bearing 37 for the spindle 38 of the winding drum 39 upon which is wound the chain or like device extending to the brake rod or other brake mechanism. Above the drum 39 the driven 70 gear 40 of the gearing device such as shown in the aforesaid Letters Patent is mounted, which gear is in mesh with the companion or driving gear 41 that has an aperture 75 through its hub which is counter part of shaft or mast 14 so as to permit the latter to be moved vertically through the gear 41 but to rotate said gear whenever said shaft or mast is rotated to apply or release the 80 brake.

85 While I have herein disclosed a preferred or typical embodiment of my invention it will be obvious that modifications thereof may be made without departing from the principles involved, and I desire it understood that changes that may be made are contemplated as coming within the scope of the appended claims.

What I claim as new is:

1. In a railway car brake a drop shaft 90 mechanism consisting of a vertically movable shaft, upper and lower gear housing members, a stirrup on the lower member in which said shaft is guided, and a gate hinged to said stirrup and normally transverse in the axis of said shaft to support the latter upon its lower end, said gate adapted to be raised to permit the shaft to be moved past the same.

2. In a railway car brake a drop shaft 100 mechanism consisting of a vertically movable shaft, upper and lower gear housing members, a stirrup on the lower member in which said shaft is guided, and a gate hinged adjacent one edge to said stirrup, and means projecting from said stirrup to support an unhinged portion of said gate in the normal position of said gate being transverse to the axis of said shaft whereby to support the same upon its lower end, and said gate being adapted to be raised upon its hinge from said supporting means to permit the lower end of the shaft to be moved past the same.

3. In a drop shaft brake mechanism a vertically disposed rotatable shaft adapted to be moved from an upper to a lowered position, an end-sill having a horizontally elongated slot therein, a pawl and ratchet the latter of which is positioned partially in said slot and through which said shaft extends, a hinged gate normally engaged with the lower end of said shaft to support the same in its upper position, and a stirrup secured to said end-sill in which said gate is mounted.

Signed at Chicago, in the county of Cook, and State of Illinois, this 10th day of March, 1925.

SVEN JULIUS STRID.
